UNITED STATES PATENT OFFICE

GUIDO FORNACA, OF TURIN, ITALY; LUIGI FORNACA, EXECUTOR OF SAID GUIDO FORNACA, DECEASED, ASSIGNOR TO FIAT SOCIETA ANONIMA, OF TURIN, ITALY

MEANS FOR SIMULTANEOUSLY OPERATING THE VALVES IN INTERNAL COMBUSTION ENGINES

Application filed March 20, 1926, Serial No. 96,228, and in Italy March 23, 1925.

This invention provides improved mechanism for simultaneously operating two (or more) valves in an internal combustion engine, characterized in that said valves are equipped with a cross piece guided by a central stem and actuated by cams acting symmetrically with respect to the guiding axis, so that no bending stress will be generated on the valve and guiding stem.

10 Preferably, said guiding stem engages, at one of its ends, in a socket in the cylinder head while its other end is connected with the camshaft by means of a yoke formed in two parts and easily removable.

15 Under this arrangement the guiding member is practically independent of the cylinder head but is, on the contrary, dependent on the position of the camshaft; whereby a simpler construction and a greater precision are attained.

20 As the cams work always in pairs (or sets) and in a perfectly symmetrical way with regard to the guide axes, abnormal stresses of the guides are avoided and wear is minimized 25 while all inconveniences due to the formation of play between the rubbing parts are done away with.

The annexed drawings shown diagrammatically and by way of example a constructional form of the improved valve mechanism.

25 Fig. 1 is a vertical section in the plane A—B of Fig. 2.

30 Fig. 2 is a side view, partially in section, in the plane C—D of Fig. 1.

35 With reference to the drawings, 1 denotes the engine head, each engine cylinder being provided with four valves, namely two suction and two exhaust valves. The suction 40 valves 2 and 2' and the exhaust valves are operated from two separate camshafts 3, and the cams 4 on each camshaft work in pairs on cross pieces 5 arranged above the valves, one for each pair. Each cross piece has two tappets 6 and a guide 7, the latter being slideable on a stem 8 held, at its lower part, in a socket 9 in the head 1 and, at its upper parts, by a two part yoke 10, 11 loosely mounted 45 on the camshaft 3 between the corresponding cams 4, 4.

The valves are normally held against their seats 15 by means of double springs 16.

Under the action of the cams 4, each cross piece 5 is pressed at two points symmetrically disposed with respect to the axis C—D of the guide stem and will therefore be depressed to open the valves without producing any stress tending to bring it in an inclined position, thus permitting an easy work of the guide.

55 The stem 8 acts like a beam supported at both ends and loaded in proximity to one of its supports (the yoke 10, 11) and is therefore in the best condition to withstand the stresses generated by the cam, the moment of which will be of little importance 60 owing to the proximity of the support.

65 An advantage of this arrangement is that should a spring break, the cross piece may still work regularly through the efficiency of 70 the guide.

What I claim is:

75 In a valve mechanism for internal combustion engines, the combination of a cylinder head having a socket formed therein, a pair of valves in said head, a cross piece connected to the stems of the valves, a camshaft above the cross piece in the plane passing through the axes of the valve stems, two cams on the shaft engaging the cross-piece, and a guide for the latter loosely hung on the shaft between the two cams and having its free end extending into and guided by the socket on the cylinder head.

80 In testimony that I claim the foregoing as 85 my invention I have signed my name.

GUIDO FORNACA.
